(57) **CLAIM**

The ornamental design for a tripod, as shown and described.

DESCRIPTION

FIG. 1 is a top, front and left side perspective view of a tripod showing our new design, with the legs in a stowed configuration;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof;

FIG. 7 is a left side elevation view thereof;

FIG. 8 is a top, front and right side perspective view thereof;

FIG. 9 is a top, rear and left side perspective view thereof;

FIG. 10 is a bottom perspective view thereof;

FIG. 11 is a top, front and left side perspective view thereof, shown with the tripod legs in an extended configuration;

FIG. 12 is a front elevation view thereof;

FIG. 13 is a rear elevation view thereof;

FIG. 14 is a top plan view thereof;

FIG. 15 is a bottom plan view thereof;

FIG. 16 is a right side elevation view thereof;

FIG. 17 is a left side elevation view thereof;

FIG. 18 is a top, front and right side perspective view thereof;

FIG. 19 is a top, rear and left side perspective view thereof;

FIG. 20 is a bottom perspective view thereof;

FIG. 21 is a top, front and left side perspective view thereof, shown with the tripod legs in a collapsed and open configuration;

FIG. 22 is a front elevation view thereof;

FIG. 23 is a rear elevation view thereof;

FIG. 24 is a top plan view thereof;

FIG. 25 is a bottom plan view thereof;

FIG. 26 is a right side elevation view thereof;

FIG. 27 is a left side elevation view thereof;

FIG. 28 is a top, front and right side perspective view thereof;

FIG. 29 is a top, rear and left side perspective view thereof;

FIG. 30 is a bottom perspective view thereof;

FIG. 31 is a top, front and left side perspective view thereof, shown with the tripod in an alternate configuration and in condition of use;

(Continued)

FIG. 32 is a top, front and left side perspective view thereof, shown with the tripod in a second alternate configuration and in condition of use;

FIG. 33 is a top, front and left side perspective view thereof, shown with the tripod in a third alternate configuration and in condition of use;

FIG. 34 is a top, front and left side perspective view thereof, shown with the tripod in a fourth alternate configuration and in condition of use;

FIG. 35 is a top, front and left side perspective view thereof, shown with the tripod in a fifth alternate configuration and in condition of use with a camera disclosed in broken lines to illustrate an environment; and,

FIG. 36 is a top and rear perspective view thereof, shown with the tripod in a sixth alternate configuration and in condition of use.

The broken lines depict portions of the tripod in which the design is embodied that form no part of the claimed design. The broken lines showing a camera in FIGS. 35 and 36 represent environmental structure and form no part of the claimed design.
